UNITED STATES PATENT OFFICE.

LÉON SAIVES, OF BILLANCOURT, FRANCE, ASSIGNOR TO LOUIS RENAULT, OF BILLANCOURT, FRANCE.

LUBRICATION OF INTERNAL-COMBUSTION ENGINES.

Application filed April 1, 1924. Serial No. 703,390.

To all whom it may concern:

Be it known that I, LÉON SAIVES, citizen of the French Republic, residing at Billancourt, Department of the Seine, in France, have invented certain new and useful Improvements in or Relating to the Lubrication of Internal-Combustion Engines; and I do hereby declare the following to be a full, clear, and exact description of the invention, such as will enable others skilled in the art to which it appertains to make and use the same.

This invention relates to the lubrication of internal combustion engines, and more particularly to apparatus for purifying the oil used for that purpose. Most internal combustion engines either of the explosion or combustion type are provided with a system of lubrication by oil circulation under pressure, the oil being drawn from the lower casing by a pump driven by the engine. This pump forces the oil into lubricating pipes which feed oil to the several rubbing surfaces, which it is desired to lubricate. After having passed over these surfaces, the oil drains back to the casing to be again drawn up by the pump and to restart the same cycle.

In this method of use the oil loses a part of its lubricating qualities. Firstly, it takes up very fine dust which arises from the wear of the rubbing surfaces, secondly, by contact with parts at a high temperature such as the cylinders and pistons it undergoes a partial decomposition producing carbonaceous particles the molecular structure of which resembles that of coke; thirdly, when combustion or explosion takes place there is always a small quantity of fuel, which is not completely burnt, and there remains in the explosion chamber small carbonaceous particles, a part of which descends between the cylinder and the piston rings and mixes with the oil; fourthly, the air for supporting combustion sucked in by the engine very often contains abrading dust, a part of which descends similarly into the oil.

For these several reasons it can readily be imagined that the lubricating oil quickly loses its lubricating qualities, the foreign matters (dust from wear, carbonaceous particles or atmospheric dust) which become

mixed with it, constituting a very serious wearing agent.

To restore its original properties to the oil it is thus necessary to remove all foreign matters, which may have become mixed with it however fine they may be.

It is indeed to be noted that it is the finest particles which are the most dangerous, since they generally consist of dust from wear or gritty atmospheric dust.

The introduction of a metallic gauze filter which is usually located in the forcing circuit of the pump is not able to keep back all the dust or carbonaceous particles in question, for the dust and particles are so minute that they pass through the meshes of the filter.

Only suitably arranged centrifugal apparatus is able to keep back this matter, because such apparatus effects separation by the action of the differences of specific gravity between the foreign matters and the oil. The size of the impurities to be kept back thus no longer comes into question. On the other hand, the force of separation of these foreign matters can be regulated at will by running the apparatus more or less rapidly.

But in order that the centrifugal apparatus may produce its full useful effect it is necessary that the oil should be centrifugalized at the highest temperature possible, because its viscosity is then considerably diminished and such foreign matter as will separate under the action of centrifugal force at a given temperature no longer separates out at a temperature a few degrees lower.

This consideration thus involves the necessity of adapting the apparatus in such way as to form part of the engine casing or at any rate of uniting it with this casing by very short pipes. The provision of an external centrifugal apparatus working in the open air with tank, circulating pump and pipes is unsuitable for this reason.

In order to fulfil its object and to completely purify the lubricating oil, the centrifugal apparatus should thus be located in such a way that the whole of the lubricating oil is obliged to pass through it before reaching the rubbing surfaces, it should also be located as near as possible to said

surfaces so that the path of the purified oil may be the shortest possible. For reasons of economy it ought also to be such that its working does not entail an expenditure of 5 additional oil.

The accompanying drawing shows by way of example an engine fitted with a centrifugal apparatus which fulfills the conditions enumerated above. The engine is shown in 10 transverse section.

The cylinders are shown at 1, the upper casing at 2, and the lower casing at 3. The purifying apparatus is shown in detail at the left side of the drawing. It consists of a 15 body 6 which may form part of the upper casing 2; this body is covered by a bell 7, held in place on the body 6 by a stirrup 8 and a clamping screw 9, or by any other means capable of rapid taking apart. Inside the 20 body and the bell is a rotor 10 closed by a detachable bottom 11 and rotatable about the axis X Y, by means of the upper pivot 12 and the lower shaft 13. This shaft, which rotates in the bearings 14, 15, is provided 25 at its upper end with driving dogs 16, engaging in corresponding slots in the bottom 11. It is also provided at about its middle with a helical pinion 17, gearing with another pinion 18, keyed on the horizontal shaft 19, 30 which is driven by the two pinions 20, 21, the latter of which is keyed on the shaft 22 driven by the engine, and which may be the cam shaft.

Inside the rotor 10 is an inverted container 23 provided with apertures 23' in its lower portion and with radial wings 23" on its periphery. Above this tank is a cylindrical filter of wire gauze 24. The upper part of the rotor is provided with small 35 openings 25 which start quite close to the axis X Y.

The vertical shaft 13 driving the rotor is bored with a passage 13', the lower part of 40 which opens into the chamber 26, communicating with the delivery of the oil-circulating pump 27. Finally the lower part of the body 6 communicates with a delivery pipe 45 28 which supplies oil to the bearings 5 of the crank shaft 4, as well as to all parts to 50 be lubricated.

The operation takes place as follows: When the engine is running the oil-circulating pump 27 delivers oil into the passage 13' in the shaft 13, which runs at a very high 55 speed owing to the multiplying gears 20, 21 and 17, 18. In order to escape the oil is forced to pass through the rotor in the direction of the arrows, and to flow out through

the openings 25, in order to pass to the delivery pipe 28 and to lubricate all rubbing surfaces.

Now, the rotor, which is driven by the shaft 13, receives a very rapid rotary motion, and the oil which passes through it is forced to participate in this same motion by the 60 wings 23" of the container 23, and during its rise into the rotor all the heavier particles under the action of centrifugal force adhere to the inner surface of the rotor and remains there while the purified oil escapes by the 65 opening 25.

The object of the cylindrical filter 24 is to 70 keep back the light impurities in the oil such as fibres from rags, which may be inside the engine after erection; this object is entirely subsidiary.

The cleaning of the apparatus is done in the following way, the engine being stopped, the screw 9 is slackened, which permits of the stirrup 8 being tipped over, freeing the bell 7. It is then possible to take out the rotor 10 by lifting it vertically. After the bottom 11 has been detached, the dirt collected inside the rotor 10 is removed and it only remains to fit the members together again in 80 the reverse order.

It is to be clearly understood that the arrangement of the centrifugal purifier is not strictly limited to the preceding description; for example the oil might enter at the top instead of at the bottom. Generally speaking any arrangement of centrifugal purifier working under pressure in which partitions force the oil to flow towards the periphery of the apparatus so as to acquire the greatest 90 linear velocity and in which the oil can only escape near the centre, whilst the dirt remains in the apparatus is within the scope of the invention.

Claim—

An oil purifying apparatus for internal combustion engines comprising a base constituting an extension of the engine crank case, a vertical shaft bearing integral with the base, an oil supply pipe connecting the lower part of said bearing with the oil reservoir in the crank case, a hollow shaft journaled in said bearing, a rotor detachably connected to the upper open end of said shaft, a casing removably secured to said base, delivery pipes connected to said base, and gearing connecting said hollow shaft with a rotating part of the engine.

In testimony whereof I affix my signature.

LÉON SAIVES.
